(57) **CLAIM**

The ornamental designs for conspicuity tag, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a first ornamental design for a conspicuity tag;

FIG. 2 is a rear view thereof;

FIG. 3 is a right-side view thereof;

FIG. 4 is a left-side view thereof;

FIG. 5 is a top view thereof;

FIG. 6 is bottom view thereof;

FIG. 7 is a left upper perspective view thereof;

FIG. 8 is a front perspective view thereof;

FIG. 9 is a front view of a second embodiment of an ornamental design of a conspicuity tag;

FIG. 10 is a rear view thereof;

FIG. 11 is a right-side view thereof;

FIG. 12 is a left-side view thereof;

FIG. 13 is a top view thereof; and,

FIG. 14 is bottom view thereof.

**1 Claim, 14 Drawing Sheets
(8 of 14 Drawing Sheet(s) Filed in Color)**
